Primary Examiner—Robert M Spear*Assistant Examiner*—Barbara B Lohr(74) *Attorney, Agent, or Firm*—Albert Bordas, P.A.(57) **CLAIM**

The ornamental design for a bamboo vertical blind, as shown and described.

DESCRIPTION

FIG. 1 is a front elevational view of the bamboo vertical blind; FIG. 2 is a left-side elevational view thereof, the right-side elevational view being a mirror image thereof;

FIG. 3 is an enlarged, partial view of the upper and lower portion of the bamboo vertical blind of FIG. 1, the view being broken away for ease of illustration;

FIG. 4 is a left side elevational view of FIG. 3, the right side elevational view being a mirror image thereof; and,

FIG. 5 is a top plan view of FIG. 3, the bottom plan view being a mirror image thereof.

The depiction in FIGS. 3 and 4 of the detailed contours of the bamboo knuckles are understood to represent the contours of all knuckles shown in the drawing views.
